SANITARY NAPKIN HOLDER

Josephine A. Wald, Detroit, Mich.

Application January 18, 1947, Serial No. 722,808

2 Claims. (Cl. 128—289)

1

The present invention relates to a sanitary napkin holder in which an impervious, elastomeric catamenial pouch is provided to hold a disposable absorbent pad, the holder being such that it may be worn inconspicuously with comfort, convenience and confidence.

Conventional catamenial pouches heretofore suggested have not been wholly satisfactory due to the fact that their supporting straps frequently are encumbered with bulky snaps, buckles, or other adjusting devices, and are difficult to conceal as well as uncomfortable to wear. In addition, the supporting straps usually are not properly designed to conform to normal bodily movements with the result that the pouch is easily displaced with consequent chafing and embarrassment to the wearer. The pouch itself frequently is not properly designed or formed of proper materials to assure its cooperation with the supporting straps of the device to adequately and securely hold the disposable absorbent pad or to permit the convenient replacement thereof.

An important object of the present invention is to provide an improved sanitary napkin holder which permits the appliance to be inconspicuously and conveniently worn with comfort and in which the cooperative construction and arrangement between the pouch and supporting straps permits the holder to conform readily to the bodily contours of the wearer and at the same time permits complete freedom of movement for the hinge points of normal bodily movement, thereby to eliminate displacement of the device and body chafing therefrom.

Other objects of the present invention are to provide improvements in a sanitary napkin holder in which the pouch is suspended by narrow, flat, resilient straps, adapted to conform readily and inconspicuously to the body contours of the wearer; and in which the pouch itself comprises an impervious resilient plastic film specially constructed to prevent curling or rolling at the edges thereof and particularly adapted to conform to the pelvic girdle of the user and to hold its position during normal bodily movement of the user.

Further objects of the present invention are to provide a sanitary napkin holder having a pocketed catamenial pouch which is particularly adapted to retain a disposable pad or sanitary napkin in place while the pouch is being worn, and to permit ready replacement of the pads without necessitating the complete removal of the holder from the body of the wearer.

Other objects of this invention will appear in

5 the following description and appended claims, reference being had to the accompanying drawings forming a part of this specification wherein like reference characters designate corresponding parts in the several views.

Fig. 1 is a vertical section through the pouch of a sanitary napkin holder embodying the present invention, shown in position on a portion of a human figure in phantom, and also showing the human figure with one leg raised and the pouch in the relaxed position in phantom for replacing a pad.

Figs. 2 and 3 are reduced scale front and rear views respectively of the napkin holder of Fig. 1 and shown in position on a portion of a phantom human figure.

Fig. 4 is essentially a top view of the napkin holder shown in Fig. 1.

Before explaining the present invention in detail it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

An essential and an important feature of the present invention is to provide a sanitary napkin holder which snugly conforms to the crotch and pelvic girdle with a minimum coverage consistent with positive protection to the wearer, and which is supported by elastic straps that are particularly adapted to grip the body immediately above and below the hips so as to allow complete freedom of movement of the body at the waist and hips with a minimum of movement or strain on the pouch and supporting straps.

In order to illustrate clearly the advantages and application of the present invention, a sanitary napkin holder employing a specific embodiment thereof is described below in reference to the drawings wherein the pouch, indicated generally by the numeral 10, is joined at the front along the midline of the body by the elastic body encircling strap 11, and at the rear by the two elastic leg straps 12, which latter attach at 13 to the encircling strap 11 below and forward from the upper portion of the hip bones, substantially at the fold of the groin, Figs. 1 and 2.

The pouch 10 comprises a thin, impervious elastomeric membrane. It may be molded from a suitable elastomeric plastic material or it may be fabricated from a suitable sheet of such ma-

terial, such as, for example, a vinyl plastic sheet which is flexible and soft to the touch, yet is tough and resilient. It is a primary consideration to avoid bulky and cumbersome connections between the straps 11 and 12 and between the straps 11 and 12 and the ends of the pouch 10.

Fig. 1 shows the pouch 10 as normally worn over the vulva and extending forward from the coccygeal region to slightly above the lower portion of the symphysis pubis. For the sake of comfort and in order to adapt the pouch 10 to the arcuate contour of the portion of the body at which it is worn, it is important to effect a longitudinal curve to the pouch 10. Accordingly, a significant feature of the present invention is the longitudinal curvature of the body of the pouch 10, as shown in Fig. 1. The edges 14 of the pouch 10 are shorter than the length of the longitudinal mid-section of the pouch 10. If the pouch 10 is molded, the edges 14 may be provided with a rolled bead edge. If the pouch 10 is fabricated from sheet materials, the edges 14 are shirred and bound with a resilient tape.

A pocket 15 is formed by the cover flap 16 which is secured across the forward portion of the top of the pouch 10, at the front near the juncture of the pouch 10 and the encircling strap 11. A pocket 17 is formed by the cover flap 18 which is secured across the rearward portion of the top of the pouch 10 near the juncture of the pouch 10 with the ends of the leg straps 12.

The ends of an absorbent pad 19 are fitted within the pockets 15 and 17 so that when the pouch 10 is worn, the opposite ends of the pad 19 are held by the flattening of the pockets 15 and 17. Thus slight movements of the body relative to the pouch 10 will not cause displacement of the pad 19.

Used pads 19 may be replaced without entirely removing the sanitary napkin holder. The rear portion of the pouch may be swung downward and forward by slipping the leg strap 12 downward on one side. Removal of a pad 19 is facilitated by raising one leg to the position shown in phantom, Fig. 1. This gives ready access to the pouch 10 to permit replacement of the pad 19.

Since downward movement of the leg straps 12 readily swings the pouch 10 and pad 19 out of position, it will be apparent that normal evacuation of the bowels and bladder is possible without removing the holder from the body and without removal of the pad 19 from the pouch 10.

The supporting straps 11 and 12 are so designed and located that they do not bind or limit bodily movement of the wearer. The straps 11 and 12 are particularly located with respect to the body so that they do not interfere with the freedom of the hinge points thereof. At the same time, movement or torsion is minimized between the pouch 10 and the supporting straps 11 and 12.

The encircling strap 11 crosses the mid-line of the body in front and below the upper portion of the symphysis pubis and passes upward on either side essentially along the fold of the groin and just over the hip to complete a circle across the lumbar region at the small of the back. Bending or torsion at the waist will therefore have little effect in moving the encircling strap 11, since it encircles the substantially inarticulate pelvic girdle and is thereby movable essentially only as a unit with the pouch 10. Accordingly, relative movement of the strap 11 and pouch 10

with respect to the body is virtually eliminated. This eliminates chafing as well as the danger of displacement of the pouch 10 and the absorbent pad 19.

5 The position of the encircling strap 11 along the fold of the groin on either side of the pouch 10 not only provides optimum comfort by resting clear of the abdomen, but also avoids movement that might otherwise be imparted to the strap 11 and pouch 10 upon movement of the legs. Since the forward portions of the strap 11 lie along the hinge folds of the legs, it is apparent that the legs may be freely moved without causing appreciable movement of the strap 11.

10 The leg straps 12 also are positioned so that movement of the legs does not cause appreciable movement of the leg straps 12 and the rear portion of the pouch 10 is held in place during all leg movements. The forward portion of each strap 12, from the point 13 to the side of the thigh, lies along the hinge line of the leg and is therefore only slightly affected by movement of the leg. Extreme movement of the legs, such as kicking upward, tends to raise the front portions of the straps 12, which movement is resisted by the rear portion of the strap 12 to pull the pouch 10 more tightly into contact with the body. The rear portions of the straps 12 extend angularly downward to a position below the coccyx where they are joined at the rear of the pouch 10 and thus are relatively immobile with respect to the pelvic girdle regardless of movement of the legs.

15 It is to be noted in this connection that the angularity of the juncture between the leg straps 12 and the rear of the pouch 10 comprises an important improvement in the construction of sanitary napkin holders of the type of the present invention, and holds the pouch 10 positively over the body region of the wearer to be protected. As is apparent from Fig. 3, the tension in the straps 12 exerts equal components of lateral force tending to hold the rear of the pouch 10 on the mid-plane of the body, and likewise exerts a vertical component of force which prevents the rear portion of the pouch 10 from working downward as a consequence of repeated alternating movements of the buttocks during walking or other normal bodily activities. Thus the present invention permits recreational activities such as dancing, for example, and is thereby particularly suited for the athletic woman.

20 The tension on the forward portion of the pouch 10 and its connection with the strap 11 is balanced at the rear of the pouch 10 by an equal tension comprising the vertical component of force of the straps 12, so that the rear of the pouch 10 is maintained over the base of the coccyx as required for adequate protection to the wearer. Thus the pouch 10 is held tightly to the wearer's body, and as shown in Figs. 1 and 3, the bifurcation and angular disposition of the straps 12 at the base of the pouch 10 prevent the latter from wedging uncomfortably into the sagittal 25 crack between the buttocks.

25 Obviously, the angle between the straps 12 at their juncture with the rear of the pouch 10 will vary in accordance with the design of other portions of the holder, and may feasibly range from approximately 90° to approximately 135°. The smaller the angle, the greater will be the vertical component of force on the straps 12. With the arrangement of resilient straps 11 and 12 shown, an angle of approximately 135° between the straps 30 12 at their juncture with the pouch 10 has been

found suitable to support the latter as desired and to prevent its working downward.

Another important feature of the present invention is its freedom from buckles, snaps and other conspicuous encumbrances which are not only a source of great irritation to the wearer, but are also the principal source of trouble encountered in replacing sanitary pads, since the pad tape becomes matted and entangled in the snaps and buckles. The device is adapted to be made in various sizes in the manner of other articles of clothing and therefore requires no additional adjustment for the particular wearer, although the resiliency of the straps 11 and 12 will accommodate minor adjustments in size. Accordingly, the device may be worn inconspicuously under light or abbreviated clothing, such as sport clothes, bathing suits, and the like.

From the foregoing, it will be seen that I have provided important improvements in a holder for disposable sanitary napkins, which provides positive protection yet which is particularly adapted by its improved construction and arrangement of parts to be worn inconspicuously without chafing or danger of moving out of place. The suspension for the impervious pouch conforms to the substantially inarticulate pelvic girdle so that all hinged points of the body are free to move without causing displacement of the holder.

I claim:

1. In a sanitary napkin holder adapted to conform and to be movable as a unit with the essentially inarticulate pelvic girdle of the wearer, the combination of a longitudinally curved pouch of soft impervious elastomeric sheeting adapted to hold a disposable absorbent pad and to extend from the base of the coccyx to the base of the symphysis pubis, a resilient body encircling strap secured to the forward portion of said pouch and extending in both direc-

tions around the body of the wearer from the region of the pubis and over the hips and across the lower portion of the back, and means to exert a vertical component of force at the rear of said pouch to prevent downward movement thereof and to exert balanced horizontal components of force to prevent lateral displacement thereof so as to support the rear of said pouch over the base of the coccyx and including a pair of resilient leg straps symmetrically secured angularly to each other at the rear of said pouch and extending angularly and laterally from each other and upward and forward across the buttocks, the forward end of each leg strap being attached in the region of the groin of its respective thigh to said body encircling strap.

2. The combination as claimed in claim 1 and being further characterized in that said pouch is essentially the length of an absorbent napkin to be held thereby, in that flat pockets are provided by the ends of said pouch to receive the ends of said napkin and to grip the latter upon flattening of said pockets against the body of the wearer, in that the lateral edges of said pouch are shorter than the longitudinal mid-section thereof so as to effect said longitudinal curve for conforming to the body contour of the wearer, and in that means are provided to prevent outward curling of the edges of said impervious elastomeric pouch and include an elastic bead along the lateral edge portions thereof.
